BURIAL GARMENT

Hazel H. Woods, Greenville, Ohio, assignor of
forty-eight per cent to Adam W. Lynn, Arcanum, Ohio

Application August 17, 1936, Serial No. 96,529

2 Claims.

(Cl. 2—64)

This invention relates to wearing apparel and more particularly to a burial garment.

It is one object of this invention to provide a garment of novel construction that may be readily and easily assembled on the body of a dead person without distorting or interfering with the natural position of the various limbs of the body.

Another object is to provide a burial garment that shall be so constructed as to permit the arm or leg portions of the garment to be opened so as to receive the corresponding limbs of the body and which can be readily and easily assembled about such limbs.

A further object is to provide a garment having the above characteristics having novel fastening means for connecting the co-operating edges of the garment.

A still further object is to provide a garment having the above characteristics that shall be simple in structure, durable, desirable by the trade for the purpose for which it is intended, and which can be employed in the manufacture of very cheap or expensive burial garments.

The above and other objects will be made apparent throughout the further description of the invention when taken in connection with the accompanying drawings wherein like reference characters refer to like parts. It is to be distinctly understood that the drawings are not a definition of the invention but illustrate certain forms by which the invention may be carried out. The scope of the invention will be defined by the appended claims.

In the drawings:—

Figure 1 is an exploded view showing the upper portion of an outer garment in open position for receiving a human body and an undergarment in assembled position,

Figure 2 is a perspective view of an under garment embodying the invention,

Figure 3 is a front elevational view of a dress embodying the invention,

Figure 4 is an enlarged fragmental view showing one manner of connecting the co-operating edges of the sleeve opening and the opening in the adjacent body portion of the dress, and

Figure 5 is a front elevational view of a man's trousers having the legs thereof partly disassembled.

Referring to the drawings, Figures 1 to 4 inclusive illustrate one form of a garment or a dress for a female person wherein 10 indicates a dress in its entirety and 11 indicates an undergarment in its entirety. The dress is preferably

constructed to provide an opening 12 in the front thereof extending throughout the vertical height of the front of the dress. Such opening may appear at any point between the two side seams according to whatever design of front may be desired. Suitable means, such as snap fasteners 13, may be employed for detachably connecting the laps 14 and 15 and maintaining the co-operating surfaces in dress position. In order that the shoulder and arm portions of the dress or coat 10 may be opened up to receive the corresponding portions of a body, there is provided a lateral or horizontal opening 16 across the waist portion of the dress. Preferably a belt 30 normally conceals the opening 16 and connecting means 17. The opening 16 is provided with means 17 for detachably connecting the co-operating portions of the dress forming the opening 16. Each of the sleeves is slit preferably on its inner side throughout the length of that portion of the sleeve as shown 20 at 18. The opening or slit 18 in the sleeve portion is adapted to join and coincide with an opening 19 provided in the side of the dress which is adapted to connect and extend into the opening 16 across the front of the dress. Suitable closure means, such as 31, are provided for openings 19. The slits or openings 18 in the sleeves are preferably provided with the well-known hookless fastener means 21 for connecting or disconnecting the co-operating edges of the sleeves, but any other modern type or desired means may be employed which are suitable for the purpose. However, by providing this type of means for closing the opening 18 in the sleeve, the sleeves are caused to fit the arm of a body in smooth 35 dress relation. The opening 16 across the front of the dress and the co-operating opening 19 on each side of the dress may be provided with any suitable closing device, but as shown are provided with snap fasteners 17 for connecting the adjacent edges or laps of the dress.

Referring to Figure 1, it can now be readily understood that the dress 10 may be opened up and laid out flat on a table or the like by opening the hookless fasteners 21 or other closure means 45 that may be used in the sleeves and the snap hooks 13 and 17 provided on the co-operating laps of the openings 12, 16 and 19. Then the body of the dead person may be superimposed on the garment in the proper position and the co-operating portions of the garment folded around the corresponding parts of the body and fastened without need of moving the limbs of the body.

The undergarment 11 for the purpose of illustration may be constructed in one piece and 55

adapted to be folded around the main portion of a body and having its co-operating longitudinal edges lapped over to form lapped portions 22 and 23. If preferred, the design of the garment could be of the built-up shoulder type. Suitable fastening means of any desired kind, for example 26 are provided at selected points for properly assembling the laps 22 and 23 in position about the body. Shoulder straps 27 may also be provided and detachably connected to the upper rear and front edges of the garment 11 by suitable means such as snap hooks 28.

Figure 2 illustrates the detailed construction of garment 11. In this embodiment the shoulder straps 27 are of sufficient length for their purpose as shown, and the garment is formed with the laps 22 and 23 having the upper edges coinciding one with the other.

Figure 5 illustrates one form of constructing a man's trousers. In the form shown the trousers are adapted to open along each of their sides throughout the length of the trousers as shown at 29. The lap portions 31 and 32 of the trousers may be detachably connected by suitable snap hooks 33 as shown or a fastener of the type shown at 21 may be employed. When the trousers are in open position the front leg portions may be turned towards each other while laying on the table and the co-operating portions of a body 30 superimposed on the rear leg portions and thereafter the front leg portions can be readily positioned about the corresponding body portions and fastened as above described.

While there is here illustrated and described certain forms of a female garment and one form

of a man's trousers, it is to be expressly understood that these particular forms are merely employed to illustrate the invention. The invention is particularly adaptable for use with any type of garment for either male or female. It is understood that any changes, substitutions, modifications, additions and omissions in the illustrations here shown may be resorted to without departure from the spirit and scope of the invention and appended claims and without avoidance of any rights thereby defined.

What I claim is:—

1. A burial garment having front, side and sleeve portions, said front portion having a longitudinal opening which extends throughout the length of the garment, said sleeve portions having longitudinal openings extending throughout the length of the sleeve, a transverse opening in the said front and openings in the said sides of said garment for connecting and communicating with the said transverse openings and the openings in the sleeve portions.

2. A burial garment having front, side and sleeve portions, said front portion having a longitudinal opening which extends throughout the length of the garment, a transverse opening in said front portion and openings in the side of said garment, detachable means for connecting the co-operating edges of the front, transverse and side openings, and a belt extending around the transverse opening, at and over the lower ends of the side openings, said belt being vertically split along the line of the longitudinal opening.
